HOODED GARMENT

Arthur C. Herrington, Boston, Mass.

Application March 12, 1951, Serial No. 215,074

4 Claims. (Cl. 2—84)

1

This invention relates to sleeved garments, and particularly to foul weather garments that are adapted for use over other articles of apparel, and even more particularly to foul weather garments of the type having a hood attached to a jacket so as to enclose both the body and head of a person wearing the same.

An object of the invention is to provide a foul weather garment comprising a jacket and a hood attached to the jacket that is of simple construction for ease of making.

It is another object of the invention to provide a foul weather garment consisting of a jacket and a hood that is constructed from parts that have basic geometric outline whereby the garment is easily constructed and easily put together.

It is still another object of the invention to provide a garment constructed in accordance with the foregoing objects wherein the garment can be assembled with a minimum number of seams, thereby reducing labor of making and providing a garment of greater strength.

Further objects and advantages will become apparent from the drawings and the following description.

In the drawings:

Figure 1 is a three-quarter front perspective elevational view of the garment of this invention as worn by a person;

Figure 2 is a three-quarter rear elevational view of the garment as worn by a person;

Figure 3 is a front view of the garment;

Figure 4 is a rear view of the garment;

Figure 5 is a front view of the hood portion of the garment;

Figure 6 is a rear view of the hood portion of the garment;

Figure 7 is a plan view of the body of the garment;

Figure 8 is a plan view of one of the sleeves of the garment;

Figure 9 is a plan view of the hood of the garment;

Figure 10 is a plan view of the wrist-band for attachment to the body of the garment.

Figure 11 is a plan view of the waist-band for attachment to the body of the garment.

In this invention, the foul weather garment consists of a body portion 10 to which there are attached the sleeve portions 11 and a hood portion 12. The hood portion 12 is provided with a face opening 13. A waist-band 15 is provided around the bottom end of the body portion 10 and is preferably a snug fit to the person of the

2

wearer. This band may be made of elastic, if desired.

Each of the sleeves 11 is provided with a wrist-band 16 that is also adapted to be a snug fit around the wrist of the wearer, and may be of elastic material, if desired.

The hood 12 is substantially a continuation of the back of the body portion 10 of the garment so as to provide a loose-fitting portion 17 around the shoulders and neck of the wearer, which tends to trap the body heat in this area to keep the neck and shoulders warm.

The body portion 10 of the garment is illustrated in Figure 7 and is substantially quadrangular in shape, and specifically, is rectangular. The edges 20 and 21 provide the waist portion of the garment when the body 10 is folded along the median line 24, which, incidentally is the shoulder-line of the garment.

When the body portion 10 is folded on the median line 24, the upper half of the longitudinal edge 22 is brought against the lower half thereof, as is the upper half of the longitudinal edge 23 being brought against the lower half of the edge 23, these edges being seamed together along a part of their length from the waist edge upwardly to the point of juncture with the sleeve 25 placed at each side of the body portion 10.

The sleeves of the garment are each like that disclosed in Fig. 8 wherein the sleeve 25 is illustrated as being in the form of a truncated isosceles triangle. The base edge 26 of the sleeve 25 is adapted to be attached to the longitudinal edge 23 of the body portion 10 with the median line 21 of the sleeve in alignment with the median line 24 of the body portion 10, which forms the shoulder-line. The sides 28 and 29 of the sleeve 25 are seamed together, thereby forming a complete sleeve.

To provide freedom of arm movement, the base 26 of the sleeve 25 is of substantially the same length as the sleeve length, that is, the height of the triangular shaped sleeve taken along the median line 21.

Both left and right sleeves are identical so that no further description of the sleeves need be made, other than stating that a sleeve is attached to each of the longitudinal edges 22 and 23 with the median line 21 of the sleeves in alignment with the shoulder-line or median line 24 of the body portion 10.

A wrist-band 16 is secured to the line of truncation 31 of each of the sleeves 25, and may be constructed of elastic material, if desired, to provide a snug fit around the wrist of the wearer.

A waist-band 15 is secured along the waist edges 20 and 21 of the body portion 10 and may be constructed of resilient material, if desired.

The body portion 10 is provided with a quadrangular opening 35 that forms the head opening for the garment. This quadrangular opening 35 is placed with the median line 66 thereof forward of the median or shoulder-line 24 relative to the front and back of the garment.

The hood 12 of the garment is constructed from the member illustrated in Figure 9 wherein the hood member 12 consists of a base edge 36 that has straight-line portions 37, 38 and 39 connected at their ends with the two semi-circular portions 40 and 41. Projecting upwardly normal to the base line 36 are the straight edges 42 and 43 that terminate in concave arcuate edges 44 and 45. The concave arcuate edges 44 and 45 are joined at their upper ends by the convex arcuate edges 46 and 47 that form substantially a V between the edges 44 and 45.

To form the hood 12 and attach it to the body 10 of the garment, the edges 42 and 43 are seamed together, as are the edges 46 and 47, forming the seams 50 and 51 respectively, illustrated in Figure 1. The edges 44 and 45 form the edges of the face opening 13.

The straight edge 38 of the hood 12 is seamed to the rear edge 52 of the quadrangular opening 35, whereas the straight edge formed by the edges 37 and 39 upon joining of edges 42 and 43 is secured to the forward edge 53 of the opening 35. The semi-circular edges 40 and 41 are secured to the side edges 54 and 55 respectively, of the opening 35, these openings passing over the shoulder of the wearer of the garment.

From the foregoing description, it will be apparent that the garment of this invention is constructed of basic geometrical figures with a minimum number of seams to provide for simplicity of cutting of the garment and assembling of it.

While the drawings illustrate a preferred form of the garment, yet it will be understood that it is capable of alteration without departing from the spirit of the invention, and that those modifications that fall within the scope of the appended claims are intended to be included herein.

Having thus fully described my invention, what I claim as new and desire to secure by Letters Patent, is:

1. A sleeved garment, comprising, a rectangular body portion having a rectangular opening at the center thereof, substantially triangular sleeve portions having a straight line base portion thereto attached to said body portion at substantially the center of each side thereof, and a hood portion having a base edge comprising straight-line portions connected at the ends of two spaced semi-circular line portions, said straight line portions being connected to the ends of said opening and said semi-circular line portions being connected to the side of said opening.

2. A sleeved garment, comprising, a rectangular body portion having a rectangular opening at the center thereof, substantially triangular sleeve portions having the form of a truncated isosceles triangle with the straight line base portion thereto attached to said body portion at substantially the center of each side thereof, and a hood portion having a base edge connected to the periphery of said quadrangular opening and comprising straight-line portions connected at the ends of two spaced semi-circular line portions, said

straight-line portions being connected to said body portions at opposite ends of said opening therein and said semi-circular line portions being connected to said body portion at opposite sides of said opening.

3. A sleeved garment, comprising, a body portion having a rectangular opening substantially at the center thereof, sleeve portions attached to said body portion at opposite sides thereof, and a hood portion having a base edge comprising straight-line portions having their ends connected with two semi-circular line portions, straight edge portions of equal length substantially normal to said base edge, said straight edge portions terminating in concave arcuate edge portions converging toward each other, and said concave edge portions joining with convex arcuate edge portions forming substantially a V-shaped edge therebetween, said straight edge portions and said convex arcuate edges being seamed together to form a hood with said concave edges forming a face opening, said hood being secured to said body portion at the periphery of said rectangular opening with the straight-line portions of said base edge connected with said body portion at the ends of said opening and with said semi-circular line portions connected with said body portion at the sides of said opening.

4. A sleeved garment, comprising, a rectangular body portion having a rectangular opening substantially at the center thereof, triangular sleeve portions having the form of a truncated isosceles triangle with the straight line base portion thereof attached to said body portion at substantially the center of each side thereof, and a hood portion having a base edge comprising straight-line portions having their ends connected with two semi-circular line portions, straight edge portions of equal length substantially normal to said base edge, said straight edge portions terminating in concave arcuate edge portions converging toward each other, and said concave edge portions joining with convex arcuate edge portions forming substantially a V-shaped edge therebetween, said straight edge portions and said convex arcuate edges being seamed together to form a hood with said concave edges forming a face opening, said hood being secured to said body portion at the periphery of said rectangular opening with the straight-line portions of said base edge connected with said body portion at the ends of said opening and with said semi-circular line portions connected with said body portion at the sides of said opening.

ARTHUR C. HERRINGTON.
